UNITED STATES PATENT OFFICE.

JAMES A. MONTGOMERY AND GEORGE A. MONTGOMERY, OF LOS ANGELES,
CALIFORNIA.

DESIGN FOR A BADGE.

SPECIFICATION forming part of Design No. 26,965, dated April 27, 1897.

Application filed March 26, 1897. Serial No. 629,447. Term of patent 7 years.

To all whom it may concern:

Be it known that we, JAMES A. MONTGOMERY and GEORGE A. MONTGOMERY, citizens of the United States, residing at Los Angeles, 5 in the county of Los Angeles and State of California, have invented and produced a new and original Design for a Badge, of which the following is a specification, reference being had to the accompanying drawings, showing the same.

Figure 1 is a view of a badge, showing our design. Fig. 2 is a section of the same on line 2 2, Fig. 1.

Our new design for a badge consists of a 15 plate A, with a flat surface *a*, with a raised rococo border *a'*, surmounted with a crown

a'', and a shield-shaped pendent flap B, with a flat surface *b* and raised rococo border *b'* and a raised grizzly bear *b''* in relief.

The characteristic features of the design are 20 the plate with flat surface, raised rococo border, and crown, and the shield-shaped pendent with the raised rococo border and the raised grizzly bear in relief.

What we claim is—

25 The design for a badge substantially as shown and described.

JAMES A. MONTGOMERY.
GEO. A. MONTGOMERY.
